UNITED STATES PATENT OFFICE.

GEORGE RAMSEY, OF BROOKLYN, NEW YORK, ASSIGNOR TO ANCHOR CAP & CLOSURE CORPORATION, OF BROOKLYN, NEW YORK, A CORPORATION OF NEW YORK.

METHOD AND APPARATUS FOR SEALING CONTAINERS.

1,405,738.

Specification of Letters Patent. Patented Feb. 7, 1922.

Application filed October 30, 1918. Serial No. 260,226.

To all whom it may concern:

Be it known that I, GEORGE RAMSEY, a citizen of the United States, and a resident of the city of Brooklyn, in the county of 5 Kings, State of New York, have invented certain new and useful Improvements in Methods and Apparatus for Sealing Containers, of which the following is a specification.

- 10 This invention relates broadly to a method and apparatus for sealing, and more particularly to a method and apparatus for sealing glass containers and the like under a vacuum.
- 15 A principal object of the present invention is to provide a sealing machine for forming hermetic seals by means of ductile sealing members, or caps adapted for covering receptacles of glass and the like, by 20 spinning the ductile material over a resilient or plastic gasket, which is compressed by the spinning action, between the ductile member and the vessel wall.

Another object of the present invention 25 is an apparatus as previously specified comprising an annular anvil adapted to support a portion of a ductile cap or gasket retaining member, and spinning rolls mounted for revolution about and movable inwardly 30 in co-operation with the anvil whereby a portion of the gasket retaining member may be shaped between the said anvil and the said spinning rolls.

Another and equally important object of 35 the present invention is a device as previously set forth in the first paragraph and which comprises a table for the package to be sealed and means for moving the package and the spinning rolls relatively one to 40 the other, together with suitable clutch mechanism arranged to operate the spinning rolls when said rolls are in position to be effective against the bead to be spun.

Another and equally important object of 45 the present invention is an apparatus as specified, wherein the spinning rolls are adapted to have a portion of their surface shaped to conform to a portion of the work face of the anvil, in such manner that the 50 cooperation of the spinning rolls and the work face of the anvil produces a predetermined form relative to the excess metal of the bead which is displaced during the compression action of the gasket.

55 A still further object of the present in-

vention is an apparatus as specified in the first paragraph, wherein the anvil is provided with a conical work face and the spinning rolls are provided with inclined surfaces and arranged in such manner that 60 a plane including the axes of a roll and the anvil will cut the surfaces of the roll and anvil on substantially parallel lines, whereby a substantially straight-edged rim 65 is spun between the anvil and the rolls. 65

An equally important object of the present invention is the method of forming a side seal between a suitable cap and a glass container or the like, which consists in providing a closure member with a bead in the 70 skirt thereof, inserting a resilient gasket member within the bead, placing the cap and gasket member over a suitable glass container or the like, and then deforming the 75 bead by spinning the bead radially inward to compress the gasket between the spun edge of the closure and the side wall of the container.

A still further object of the present invention is a method, as above set out, of 80 forming a hermetic seal between a suitable metal closure or the like and a suitable glass container or the like, which method comprises supporting a portion of a ductile sealing member independently of the container to which it is applied, and then deforming the portion of the sealing member 85 so supported by forces applied progressively about its periphery.

A still further and equally important object of the present invention is a sealing method by which a side seal between a metal cap and a glass container or the like may be formed under vacuum by spinning a compressible gasket against the side wall of the 95 said container.

A further object of the present invention is the method of sealing a metal cap or the like on a glass container or the like, which method consists in providing a bead in the 100 skirt of the cap; inserting within the bead a gasket ring the cross-section of which is substantially rectangular; then deforming the bead by spinning a portion of the bead radially inward to restrict the diameter of 105 the bead thereby compressing the gasket; and providing a holding device resting against a portion of the bead during the spinning operation and having an upwardly inclined work face so that the excess metal 110

of the skirt will be displaced upwardly to leave the lower edge of the skirt free for removal of the gasket when it is desired to break the seal.

5 A still further and important object of the present invention is the method of sealing a metal cap or the like against the straight side wall of a glass container or the like to provide a side seal, which method comprises providing a bead in the skirt of the cap; inserting an elastic gasket within said bead; then deforming said bead by a spinning action in such manner that the first effect of the spinning on the bead is to 10 slightly compress the lower edge of the bead whereby the gasket is retained under the bead during the entire spinning operation.

Another and equally important object of the present invention is the method of forming a side seal between a suitable metal cap or the like and the straight side wall of a glass container or the like, which method comprises providing a bead in the skirt of the cap, interposing a gasket ring between 20 said bead and the straight side wall of the container, then deforming said bead by spinning to compress the bead inwardly and upwardly whereby the gasket is under radial compression forces and the excess metal 25 of the bead is displaced in an upward direction.

The present invention possesses many other advantageous features, some of which, with the foregoing, will be set forth more 30 at length in the following description, wherein will be outlined in full that form of the invention which I have selected for illustration in the drawings accompanying 35 and forming a part of the present specification.

40 In the drawings I have shown only one specific form of my generic invention, but it is to be understood that I do not limit myself to such form, because my invention 45 may be embodied in a multiplicity of forms, each being a species of my invention. It is also to be understood that by the claims succeeding the description of my invention I desire to cover the invention in whatsoever 50 form it may be embodied or practiced.

55 Reference will now be made to the drawings, wherein like characters are used to represent like parts throughout the several figures thereof.

55 Figure 1 is a side elevational view showing one form of machine by which my invention may be carried out.

60 Figure 2 is a detail view of a part of the sealing chamber and illustrating portions of the driving gears of the machine embodying my invention.

65 Figure 3 is a detail view illustrating in section a portion of the driving gears.

65 Figure 4 is a detail view of the spinning head of a preferred form.

Figure 5 is an elevational detail showing the connection between the ring anvil and the cap-holding plunger.

Figure 6 illustrates a step in the method of forming the bead prior to engagement of 70 the spinning wheel contacting with the lower edge of the bead.

Figure 7 is a view similar to Figure 6 but showing the spinning roll commencing 75 its action.

Figure 8 is a view similar to Figure 7 and shows a further step in the sealing operation.

Figure 9 illustrates the final stage of sealing, wherein the seal is completed. 80

Heretofore in the art of forming hermetic side seals between metal caps and glass packages by deforming a cap bead over a gasket, the sealing operation has been performed by use of chucks and dies constructed to be operated under heavy pressure and to displace and deform the bead by compression action operative simultaneously upon the entire bead. In this type of action there has been considerable difficulty experienced 85 due to breakage of glass because the operation where carried out by chucks and dies does not admit of local independent treatment of the bead, which is necessary where the glass is out of round, or either under 90 or over size. Because of these facts it was

heretofore necessary that glass packages be definitely sized within very narrow limits in order to effect a proper seal without 95 breakage. In the manufacture of glass containers such limits in size and shape increased the number of condemned pieces and thus slowed down production and increased cost. Another and serious difficulty 100 encountered with the die action is the liability of the die to bite somewhat quicker on the one side of the cap than on the other and to displace the metal of the cap in such manner as to form an uneven seal which is 105 bad in appearance and often is not hermetic. 110

A still further difficulty with the chuck and die seal is the great force necessary to be exerted and the large amount of energy expended in forming such a seal. Under this prior type of sealing mechanism the 115 ordinary jar cap requires several thousands of pounds of pressure and if the parts are slightly out of adjustment this pressure may crush the packages in a vertical direction

120 by a portion of the sealing force coming directly on the package instead of on the bead of the cap. Because of the large forces used the dies and chucks necessarily are subjected to considerable wear and since small variations in a seal may be disastrous, these 125 parts must be renewed with considerable frequency.

120 In substantially all cases seals of the character specified are made in a vacuum chamber where the air under the cap is exhausted 130

prior to the sealing operation, and a relatively high vacuum is maintained under the cap (provided the seal holds) after the seal is completed. Another difficulty which 5 has been encountered is due to small hair lines or crizzles on the sealing surface of the glass. The chuck or die type of seal is a squeezing action due to forcing the bead through dies or by clamping portions of the 10 bead and closing the jaws of the chuck like a vise. By this squeezing action the material of the gasket in most cases is not forced into the hair lines on the glass but lies over these hair line grooves, so that a very small 15 leakage occurs through these minute grooves and under the gasket. This leakage after a time breaks the vacuum and all of the advantages due to a vacuum packing are lost.

The present invention solves the difficulties of the prior art by the method of 20 forming the sealed bead in accordance with method steps which will hereinafter be set out in detail, and more particularly under the action of radially applied yielding 25 forces that are effective at any given instant on a very small portion of the bead and which forces are carried around the bead in such manner that during a given period of time the entire bead has been locally 30 subjected to these forces. Under these conditions the bead is locally and progressively treated and the gasket receives a kneading action which forces it intimately into engagement with the side wall of the container 35 thereby closing all surface irregularities such as crizzles or surface hair line grooves and at the same time subjecting the gasket to pressure, which pressure is sustained by the metal bead lying over the gasket. The action of these forces is such as to 40 distort the original cap bead into a sealing bead, which is of less diameter than the original conformation and which is of such form as to sustain the gasket under compression.

One form of mechanism by which the method may be carried out is a spinning head, preferably mounted within a vacuum chamber, and constructed in such manner 45 that when a suitable package with a suitable cap and gasket thereon is brought into the zone of the spinning wheels, the spinning mechanism is rendered effective to re-form the gasket-containing bead toward the side 50 wall of the package. This spinning action does not begin until after the vacuum chamber is closed, a vacuum formed therein, and sufficient time has elapsed to permit the withdrawal of air from the package to be 55 sealed. Preferably the spinning action begins at the lower edge of the bead and progresses inwardly and upwardly thereby gradually compressing the gasket and displacing the metal in the skirt of the cap upwardly in such manner that the gasket and

the excess metal of the bead are accessible when it is desired to break the seal and remove the cap from the container. More particularly, one form of apparatus for carrying out the method comprises a type of machine with gear mechanism adapted to be connected by a positive clutch with driving devices which are effective when a pedal is operated to close a door to the vacuum chamber. The driving devices lift the package 70 to be sealed into the zone of the spinning mechanism for forming the seal. Prior to the commencement of the formation of the seal the air has been exhausted from the vacuum chamber and from the package which 75 is to be sealed. After the package has been raised into the zone of operations of the sealing devices the spinning head is rotated to deform the bead, as above specified. Under certain conditions it may be desirable to utilize two clutch mechanisms, one being operated by the pedal which closes the door to the vacuum chamber and comprises a positive clutch mechanism, the other being a friction clutch mechanism and operative 80 when the package has been lifted into the sealing zone, or when a predetermined vacuum has been formed in the sealing chamber. In this way the inertia of the moving parts 85 is taken up gradually and the spinning head 90 is set into motion without shocks or jerks, which would occur if the parts were controlled entirely by one positive clutch.

Referring now to the drawings and more particularly to Figures 2, 3, and 4, the device for forming the seal comprises a head 1 mounted upon a head shaft 2 which is 95 slidable longitudinally but is maintained against rotation as will hereinafter be described. The head 1 may carry an annular ring die or anvil 4 which may be mounted on the head by means of retaining screws 5, which pass through slotted openings 6 in the die 4 and are screw-threaded into the head 1. Preferably, a series of adjustment rings or 100 washers 7, which may be cut from suitable sheet metal or other material capable of sustaining compression forces, are arranged between the upper edge of the die 4 and the shoulder 8 on the head 1. A pressure plate 105 9 may be mounted within the annular die 4 as, for example, by means of the machine screw 10 seated in the cup 11 and screw-threaded into the head 1 with a coil spring 110 12 between the cup and the head. The cup 11 permits a yielding of the pressure plate without danger of the head of the machine screw 10 coming in contact with the cap. Under certain conditions it is entirely satisfactory to form the ring die or anvil integral 115 with the head 1, and thus eliminate the adjustment feature. The ring die or anvil 4 is constructed to engage with the upper portion of the bead 14 on the cap 15 when it is 120 in position over the mouth of the container 125 130

16, and preferably a portion of the die 4 is shaped to comprise a work face against which a part of the bead 14 may be spun to compress the ring gasket 17 between the deformed bead and the side wall of the container 16. When the container 16 with the cap 15 and the gasket 17 thereon is raised into engagement with annular die or anvil 4 the spring 12 is slightly compressed whereby 10 the pressure plate 9 presses the cap lightly upon the container 16 so as to retain it in place, but at the same time permit exhaustion of air from the package. A spinner frame 18 rests upon the head 1 and preferably is separated therefrom by bearing ring 19, which may be of any well-known type of anti-friction bearing, and is adapted to rotate upon the said bearing ring 19 and around the nonrotating head shaft 2. This 20 spinner frame is provided with radial openings, in which are mounted slidable plugs 20 that are bifurcated to carry spinning rollers 21, which are arranged opposite to the position which will be occupied by the bead 14 25 when the cap and container are in position beneath the anvil or ring die 4. The slidable plugs 20 are slotted to permit the movement of the vertical slide arms 22, each of which is provided with a diagonal opening 24, in 30 which there slides a cross-pin 25 that is secured to the plug 20. By this construction it is evident that when the slides 22 are driven through plugs 20 the cross-pins 25 traveling in the diagonal openings 24 cause 35 a radial movement of the plugs 20 which brings the spinning rollers 21 into or out of engagement with the bead 14, dependent on the movement of the slides 22. It is to be noted that each slide 22 is carried by the 40 spinning head 26, which is secured to a hollow shaft 27, which is rotatable but has no longitudinal sliding movement. The slides 22, however, are vertically slidable in the spinning head and are provided on their 45 upper ends with lock nuts 28 and are maintained in their lowermost positions with the lock nuts in engagement with the top of the spinning head by coiled springs 29. The spinning head 26 is provided with a boss 30, 50 which is hollow and forms a housing for the coiled spring 31 that rests against the spinning frame 18. From the described construction it is to be noted that the head 1 of the spinning frame 18 is yieldable toward 55 the spinning head 26 and when so moved the slides 22 drive the plugs 20 radically inwardly to perform the spinning action. It is evident that as spinning head 26 is rotated by the hollow shaft 27, the spinning frame, 60 through the connections with the slides 22, is likewise rotated, whereas the head 1 and connected parts are stationary, thereby preventing rotation of the package being sealed.

Referring now more particularly to Figures 2 and 3 as well as Figure 1 it will be

noted that the hollow shaft 27 extends upwardly through the top plate 32 of the vacuum chamber and passes through a packing gland 34. The gear frame 35, which is likewise mounted on the top plate 32 and connected to the pedestal 36, carries gearing mechanism which includes the driven gear 37 mounted on the hollow shaft 27, so that when the gear 37 is rotated the hollow shaft is thereby driven. The yoke 38 of the gear frame 35 is provided with a stub screw 39 which engages a groove 40 in the shaft 2, thereby preventing this shaft from rotating and at the same time permitting longitudinal movement of the shaft through the hollow shaft 27. The shaft 2 may also be provided with a collar 41 which limits the downward movement of this shaft. The driven gear 37 is in constant mesh with a clutch gear 42 also carried by the gear frame 35 and mounted loosely to rotate around the vertical driving shaft 44. This clutch gear 42 is provided with a flange 45 the interior surface of which is substantially conical. A cone clutch member 46 is slidably mounted on the shaft 44 but keyed to the shaft in such manner that the cone clutch member 46 is rotatable with the shaft 44. A coil spring 47 normally separates the cone clutch from engagement with the flange 45. A clutch-operating member 48 extends upwardly through the yoke 38 of the gear frame and is connected to the lever 49 by means of a pin-and-slot connection. The lever 49 is pivotally mounted on a boss 50 on the yoke 38 and is provided at its outer end with an adjusting screw 51 which contacts with the end of the head shaft 2. By this construction it will be noted that when a package with the cap thereon contacts with the head 1 and is moved upwardly to lift the head shaft 2, the end of the head shaft contacting with the adjusting screw 51 rocks the lever 49, thereby, through the connected parts, causing the cone 46 to engage the clutch gear 42; and since the cone is normally rotating, the clutch gear is rotated thereby and drives the spinning head to spin the sealing bead against the side wall of the container. By referring to Figure 1 it will be noted that the vertical shaft 44 extends downwardly through the pedestal 36 and carries on its lower end a bevel pinion 52 which is in engagement with the bevel gear 54 on the main shaft 55.

The remaining features of the machine are substantially identical with the similar functioning features disclosed in the machine illustrated in the patent to Hull, No. 1,134,065, March 30, 1915, and comprise a machine frame 56 on the base 57 of the pedestal 36 with a main shaft 55 mounted in the machine frame and a power shaft 58 likewise carried by the machine frame and above the main shaft. The power shaft is 130

equipped with a drive belt 59 and an idler pulley 60, so that where the machine is out of use for any period of time the belt may be shifted from the drive pulley to the idler pulley to obviate wear on the mechanism. Power shaft 58 carries a pinion 61 which meshes with the gear 62 secured to one portion 64 of a positive clutch, and is rotatable loosely on the main shaft 55. The other portion 10 of the positive clutch 65 is carried by the main shaft 55, which also carries a bevel gear 54 securely mounted thereon and a table lifter cam 66, adjacent which is a valve control cam 67. An operating pedal 15 68 is secured to a positive control clutch dog 69 and a link 70. The pedal 68 is normally retained in lifted position by the extensible spring 71. The link 70 is connected to the pedal 68 by means of a pin-and-slot 20 connection 72 and leads to a lever 74 for lifting the door 75 for the vacuum chamber 76. The door preferably is equipped with a guide link 77 whereby the door is maintained substantially vertical during the closing 25 operation. The table lifter cam 66 operates a lifter block 78 that is adjustably mounted on the lower end of a lifter shaft 79, which shaft extends through a suitable packing gland 80 on the bottom of the vacuum 30 chamber 76 and the lifter shaft carries on its upper end a package-receiving table 81 which may be mounted in the end of the lifter shaft as is explained in the said Hull patent. The vacuum chamber is 35 adapted to be connected to suitable vacuum apparatus through a valve 82. This valve is connected by means of the link 84 and the bell crank 85 with the valve control cam 67. A more detailed and complete description 40 of the last-mentioned parts may be obtained from the said Hull Patent No. 1,134,065.

The operation of the machine briefly described is as follows:

45 Assume a suitable power belt to be rotating the drive pulley 59, and that the gear 62 and its attendant clutch mechanism is being rotated. Assume now that the pedal 68 is depressed after a suitable container, 50 with a cap thereon and a proper gasket under the head of the cap, has been placed on the lifter table 81 in the vacuum chamber 76. The depression of the pedal first renders the positive clutch effective to enable the 55 gear 62 to rotate the main shaft at the same time closing the door 75 against the front of the vacuum chamber. This having been accomplished the vacuum line valve 82 has been opened so that suitable air exhausting 60 mechanism is effecting a vacuum in the vacuum chamber and in the package therein. The rotation of the main shaft 55 drives the bevel gear 54, and, through connected parts, the cone clutch member 46. In the meantime 65 the table-lifting cam 68 has operated to raise the lifter shaft 79 and the table 81, thereby bringing the cap bead into engagement with the anvil die 4 and the continued lifting of the package raises the head shaft 2 and consequently rocks the lever 49 which brings 70 the cone clutch member 46 into engagement with the clutch gear whereby the clutch gear takes up the rotative movement of the cone 46, consequently driving the driven gear 37 mounted on the hollow shaft 27 which in 75 turn rotates the spinning head 26 and the spinning frame 18. The lifting of the shaft 2 and the head 1 has brought the spinning rollers 21 into engagement with the lower edge of the bead 14, as shown in Figure 7. 80 The springs 29 on the slides 22 are slightly compressed so that the spinning rollers 21 are acting under compression and as the spinning head continues to rotate the bead is spun inwardly as shown in Figure 8. 85 During this spinning action it is to be noted that the bead is being carried radially inwardly and at the same time upwardly in order that the excess metal, as at 86 (Figure 8), may be formed into a flange on the sealed 90 bead. As the spinning continues, the flange 86 becomes more pronounced since the metal is gradually being spun between the spinning rollers 21 and the face of the anvil die 4, until the condition illustrated in Figure 95 9 is attained, at which time the seal is completed. Various types of seals may be made by this construction, but the preferred type is substantially the same in cross-section as the seal disclosed in the Townsend Patent 100 No. 1,242,742. This type of seal, which has a substantially straight skirt 87, enables the compressed gasket 88 to be broken and withdrawn from between the side wall of the container 16 and the skirt 87, as is explained 105 in the said Townsend Patent No. 1,242,742. This feature is desirable in that it facilitates the opening of the container when desired. Obviously, other types of seals for various 110 purposes may be formed by the mechanism herein specified.

The method by which I form this seal comprises applying yielding radial forces locally at a plurality of points upon the periphery of a suitable bead of a suitable closure and against a substantially incompressible side wall of the container through a yielding gasket under the bead; the said forces being applied locally during the sealing operation progressively about the entire 120 periphery of the said bead, whereby the bead or skirt of the closure is deformed inwardly to compress the said gasket radially and in such manner that the excess metal due to the compression actions forms a symmetric annular flange, or in some cases a groove, on the said cap. In a somewhat amplified aspect, the method also includes the removal 125 of air from the suitable container on which is placed the said closure whereby a vacuum 130

is obtained within the container; and during the period while the vacuum is maintained the yieldable gasket between the center of the closure and the incompressible side 5 wall of the container is subjected to radial compression forces applied locally around the entire skirt of the container to gradually restrict the diameter of the skirt of the cap and thereby retain the gasket under radial 10 compression to effect a hermetic seal between the side wall of the container and the skirt of the closure to retain the contents of the package sealed in vacuo.

Having thus described my invention, what 15 I claim is:

1. In a machine for sealing glass containers and the like the combination of a table for supporting a suitable container, an anvil above said table, spinning rollers adjacent 20 said anvil, mechanism for lifting said table to bring the bead of a suitable cap on a container on said table into engagement with said anvil, and means for operating said spinning rollers to deform the bead on the cap 25 against said anvil, whereby a hermetic seal is established between the cap and the container, said anvil being effective intermediate the rollers and the container wall to sustain the spinning pressure.
- 30 2. A machine for sealing suitable glass containers and the like comprising in combination a table adapted to support the container to be sealed, a sealing anvil above said table, means to secure said anvil against rotation, a spinning frame, spinning rollers mounted on said spinning frame, devices for lifting said table to raise a beaded cap on a suitable container against and into contact with said anvil, and means for operating said 35 spinning rolls against said bead to deform the same whereby the hermetic seal is established between said cap and said container, said anvil being effective intermediate the rollers and the container wall.
- 40 3. A machine for forming a side seal on a glass container or the like with a suitable cap having a ductile skirt provided with a bead carrying a moldable gasket, said machine comprising a stationary anvil encompassing a portion of the skirt of the cap and being adapted to cooperate with the upper side of the bead during sealing in order to sustain a portion of the sealing forces and to shape the upper portion of the finished deformed bead, in combination with a spinning roll movable progressively around said bead and adapted to de-form said bead by squeezing the same between the spinning roll and the said means whereby the gasket material 45 50 55 60 65

taining a vessel, a spinning roller operably arranged above the support, means for revolving the roller in an orbit and moving it radially of such orbit, and an anvil arranged for cooperation with a vessel and its closure 70 within the orbit of the roller, said anvil having a portion arranged to encompass a portion of the peripheral wall of the vessel to limit inward displacement of portions of its closure by said roller.

5. In a machine for sealing ductile caps on frangible containers, the combination with a support for the vessel to be sealed of an anvil arranged for cooperation with the vessel closure and having a rigid portion arranged to 80 encircle the peripheral wall of the vessel, said rigid portion including a work supporting face directed outwardly from the axis of the anvil, a spinning roller arranged for planetary movement about the anvil, and means for 85 operating the roller and anvil to engage a portion of the vessel closure between the roller and said work supporting face.

6. A machine for spinning a hermetic seal between a suitable metallic cap and a glass 90 container or the like, comprising in combination a head adapted to encircle the container wall and having a work-face extending outwardly from the container adapted to engage with said cap, means for preventing rotation 95 of said head, a spinner frame adapted to rotate around said cap, a plurality of radially movable plugs mounted in said spinner frame, spinner rolls carried by the inner ends of said plugs, and means for forcing said plugs inwardly under a yielding pressure to urge said rollers into cooperation with said work face on the head to move a portion of the skirt of the cap toward the side wall of the container.

7. A machine for spinning a hermetic seal between a suitable metal cap and a glass container or the like comprising in combination a support for the container with the cap thereon, a spinner mechanism adapted to rotate around the axis of the cap, said spinning mechanism comprising a spinner frame, plugs slidable radially in said spinner frame, a spinner head movable toward and from said spinner frame, and yielding means carried by said spinner head and operative to move said plugs inwardly under yielding pressure when said spinner head approaches said spinner frame, and spinner rolls mounted on the inner ends of said plugs whereby 110 the inward movement of said plugs causes said spinner rolls to spin the skirt of the cap against the side wall of the container to form a hermetic seal.

8. In a machine for spinning hermetic 125 seals between suitable metal caps and glass containers or the like the combination of a spinner frame, a plurality of plugs radially movable in said spinner frame, spinning rollers on the inner ends of said plugs, a spinner 130

head, a spring normally tending to separate said spinner head and said spinner frame, cross-pins carried by said spinner head and extending through said plugs, a wedge member connection between each cross pin and the corresponding plug, whereby when said spinner head approaches the spinner frame the movement of the cross pins causes said connection to force the plugs radially inward 10 to spin a portion of the skirt of the cap against the side wall of the container.

9. In a machine for spinning hermetic seals between suitable metal caps and the side wall of a suitable glass container the combination of a head normally adapted to engage the said cap beyond the periphery of the container wall, an anvil on said head, the work face of said anvil being formed to limit the movement of portions of the cap toward the 20 container to determine the shape of a portion of the skirt of the cap when the hermetic seal is formed, spinner rolls adapted to be moved inwardly to spin a portion of the skirt of the cap against the work face of the anvil, 25 and means for causing the spinner rolls to be effective to form the seal.

10. In a machine for spinning hermetic seals between a suitable cap and the side wall of a suitable glass container or the like the combination of a head adapted to retain the cap in position on the container, an annular anvil adjustably mounted on said head, the work face of said anvil being constructed to determine the shape of a portion of the bead 30 when the bead is completely spun, spinning rollers mounted adjacent said anvil, means for moving said spinning rollers toward said anvil under yielding pressure, a portion of the faces of said spinning rollers being constructed to coact with the work face of said anvil whereby to shape portions of the sealing bead, and means for rendering said rollers effective to re-form the side of the cap against the anvil to form a hermetic seal 35 against the side wall of the said container.

11. In a machine for spinning hermetic seals between a suitable cap and the side wall of a glass container or the like the combination of a head normally adapted to rest on the cap, means for permitting said head to slide in the direction of the axis of the cap and to prevent rotation of said head, an anvil adjustably mounted on said head in such manner that said anvil is in contact with a 40 bead on the cap when the head is in engagement with the cover portion of the cap, and spinning rolls movable with said head and rotatable around said head to spin the bead on the cap between the spinning rolls and said anvil, and means for rendering said spinning rolls effective to deform the said bead to make a hermetic seal between the cap and the side wall of the container.

12. In a machine for sealing caps on suitable glass containers and the like, the com-

bination of a pedestal, driving mechanism carried by said pedestal, a sealing chamber also carried by said pedestal, spinning devices operative within said sealing chamber, a positive clutch, driving gears adapted to be 70 rendered operative when said positive clutch is effective, means comprising a friction clutch operatively connecting said driving gears with said spinning devices, and means for rendering said friction clutch operative 75 when a suitable closure on a suitable package has been brought into the zone of operations of the spinning devices.

13. In a sealing machine, the combination of a sealing chamber, sealing mechanism therein, means for moving a container in the chamber into operable association with the sealing mechanism, means for driving the sealing mechanism, means operable by movement of a container in the sealing chamber 80 to render said driving means effective upon the sealing mechanism, actuating means for operating the driving means and for moving a container in the chamber, and manipulative means for closing the chamber and rendering the actuating means effective. 90

14. In a sealing machine, the combination of a sealing chamber, sealing mechanism therein, clutch mechanism operable to render the sealing mechanism effective, said clutch mechanism being operable by movement of a container in the chamber, and means effective to close the chamber and move a container therein to operate the clutch. 100

15. In a sealing machine, the combination of a sealing chamber, sealing mechanism therein, means for actuating the sealing mechanism, means operable by a container in the zone of operation of the sealing mechanism for controlling the operation of the sealing mechanism, and means effective to close the chamber and move a container into the zone of operation of the sealing mechanism. 105

16. In a machine of the class described, the combination of a sealing chamber, sealing mechanism therein, a clutch operable by a container in the chamber to control the operation of the sealing mechanism, means for exhausting the chamber, and means operable to render the exhausting means effective upon a container within the chamber and to render such container effective upon the clutch. 115

17. In a machine of the class described, the combination of a sealing chamber, sealing mechanism therein, a connection device operable by a container in the chamber to control the operation of the sealing mechanism, means for exhausting the chamber, and means operable to render the exhausting means effective upon a container within the chamber and to render such container effective upon the connection device. 120

18. In a sealing machine, the combination 130

- of means for supporting a vessel to be sealed, an anvil arranged for cooperation with the closure of a vessel in sealing position, said anvil having a rigid portion arranged to encompass the peripheral wall of a container in sealing position, said rigid portion including a work supporting face extending angularly relative to the axis of the anvil, a spinning roller arranged for planetary movement about the anvil, said spinning roller including a work engaging surface arranged for cooperation with the work supporting face of the anvil, and means for operating the anvil and roller to compress portions of the vessel closure between the work engaging surface and the work supporting face.
19. In a spinning machine, the combination of means for supporting a container, a spinning roller movable about a container supported thereby and operable effectively upon a sealing member on such container to displace portions thereof toward the container wall, and an anvil arranged for association with the supported container and having a work supporting surface disposed for cooperation with said roller and effective to limit displacement of portions of the closure toward the container by operation of the roller.
20. A machine for forming a hermetic side seal on a substantially cylindrical side sealing walled glass container or the like with a suitable cap having a bead carrying a moldable gasket in the skirt thereof, said machine comprising a spinning wheel for providing a sealing force to de-form said bead and compress the gasket between the de-formed portion of the skirt of the cap and the substantially cylindrical side wall of the container to form a side seal on the container, and means comprising an abutment to sustain a part of the sealing forces and to directly support a portion of the bead during the spinning operation to cause the gasket to be compressed between said means and said spinning wheel and to be forced tightly against the substantially cylindrical side wall of the glass to form a hermetic side seal.
21. In a sealing machine, the combination of a container support, an anvil disposed to encompass a container on said support, said anvil having a conical outer peripheral work face inclined toward the container wall, and a spinning roller movable about the anvil in cooperation with the work face thereof.
22. In the package closing art, the process of forming hermetic seals on frangible containers which comprises supporting a gasket of elastic material about the peripheral wall of a container by means of a ductile cap forming a closure for the latter, supporting portions of the cap beyond the peripheral extent of the container wall, then applying convergent forces to portions of

the cap locally at circumferentially separated points and moving said forces around the cap in such manner that its entire circumference is subjected thereto progressively, reducing the gasket holding portion of the cap in circumferential extent by said forces to compress the gasket against the side wall of the container, and gathering the excess metal of the cap apart from the container wall.

23. In the package closing art, the process of forming seals on frangible containers, which comprises disposing a closure of ductile material upon the container to be sealed, interposing a gasket of compressible material between portions of the closure and the side wall of the container, supporting portions of the closure independently of the container, then applying forces to portions of the closure progressively about the entire circumference thereof, deforming portions of the closure by said forces so as to compress the gasket against the side wall of the container and gathering the displaced material of the cap in the independently supported portions.

24. The method of sealing frangible containers which comprises providing a cap closure having a peripheral protruding ductile portion, disposing a charge of plastic gasket material in said portion, supporting said charge upon the container to be sealed by means of said closure cap, applying inwardly directed forces progressively to points about the perimeter of the ductile portion while supporting parts of the ductile portion against said forces, and displacing parts of the ductile portion inwardly by said forces to compress the charge of gasket material against the container wall.

25. The method of sealing glass containers and the like by a side seal cap, said method comprising providing a cap having a cover portion and a skirt portion with a bead in the skirt portion; disposing a charge of gasket material in the bead; placing the cap in position on the container; supporting a portion of the bead against movement in a direction substantially parallel to the side wall of the container; then spinning the bead inwardly to reduce the diameter of the bead and compress the gasket material between the side wall of the container and the bead to provide a side seal.

26. In the package closing art, the process of forming hermetic seals on frangible containers, which comprises supporting a gasket of compressible material about the peripheral wall of a container by means of a ductile constraining member, supporting portions of the constraining member about the peripheral wall of the container and apart therefrom, then applying forces to portions of the constraining member progressively about the entire circumference

thereof, deforming portions thereof by said forces, compressing the gasket against the side wall of the container, and gathering displaced portions of the constraining member 5 apart from the container wall.

27. A machine for forming a side seal on a glass container or the like with a suitable cap having a ductile skirt provided with a bead carrying a plastic gasket, said machine 10 comprising an anvil encompassing a portion of the skirt and having a work-face adapted to support a part of the sealing forces during the sealing operation and to re-shape a portion of the bead during sealing operations, 15 in combination with a spinning wheel adapted to be movable progressively around said bead to de-form and re-shape the bead between the spinning wheel and the anvil and compress the gasket from within the bead 20 against the side wall of the glass to form a side seal.

28. A machine for forming a side seal on a glass container or the like with a suitable cap having a bead carrying a plastic gasket in the skirt thereof, comprising an 25 anvil to support a part of the bead against movement, and means to apply radial forces to contract said bead toward the side wall of the container and to permit the gasket to 30 yield in one direction parallel to the side wall of the container.

29. A machine for forming a side seal on a glass container or the like with a suitable

cap having a bead carrying a plastic gasket in the skirt thereof, comprising a spinning 35 wheel for providing a sealing force to compress the bead radially inward to form a side seal on the container, and means between the spinning wheel and the container to sustain a part of the sealing forces. 40

30. A machine for forming side seals on glass containers or the like with a suitable cap having a bead carrying a plastic gasket in the side wall thereof, comprising a spinning wheel for providing sealing forces to 45 diminish the diameter of the bead on the cap to compress the gasket against the side wall of the container to form a side seal, and means to support a portion of the bead wall and to cause the gasket to tend to flow away 50 from said means in a direction substantially parallel to the side wall of the container.

31. A machine for forming a side seal on a glass container or the like with a suitable cap having a bead carrying a plastic gasket 55 in the skirt thereof, comprising means to support the container, an anvil of larger diameter than the said container and having a portion arranged to rest on the said bead, and a spinning wheel adapted to diminish 60 the diameter of the bead and compress a portion of the bead against the anvil to cause the gasket to flow along the side wall of the container.

GEORGE RAMSEY.
